(57) **CLAIM**

The ornamental design for a splatter shield, as shown and described.

DESCRIPTION

FIG. 1 is a perspective view a splatter shield showing my new design.

FIG. 2 is a top plan view thereof.

FIG. 3 is a front view thereof, the rear, left and right side being a mirror image.

FIG. 4 is a bottom plan view thereof.

FIG. 5 is a front view thereof, with the handle raised; the rear view being a mirror image; and,

FIG. 6 is a perspective view thereof with the handles raised. The broken lines are for illustrative purposes only and form no part of the claimed design.
